Inventor
ADOLF RIIHO,

By Townshend & Townshend
Attorneys

UNITED STATES PATENT OFFICE.

ADOLF RIIHO, OF ABERDEEN, WASHINGTON.

FOG DISPELLE.

Application filed June 14, 1926. Serial No. 115,988.

My invention relates to means for dispelling fog in advance of vehicles, either land, water or air. The primary object is the provision of a device, capable of vehicular attachment, by which a sustained blast of heated air is forcibly projected and dispersed in advance of a vehicle for dispelling fog obscuring vision in travel.

Another object is the provision in a device of this character, of a combined air pump and attached heater for the outlet thereof.

A further object is the provision in a device of this character, of means for adapting same to accomplish the storage of compressed air.

With these and such other objects in view as will be apparent from the description, the invention resides in the novel construction, combination and arrangement of parts hereinafter described and claimed, and illustrated in the accompanying drawings, wherein:—

Figure 1 is a central longitudinal section through a unit constructed in accordance with the principles of the invention, illustrating one practical embodiment thereof.

Figure 2 is a section on the line 2—2 of Figure 1.

Figure 3 is a section on the line 3—3 of Figure 1.

Figure 4 is an end elevation of the heating means.

Figure 5 is a section on the line 5—5 of Figure 1.

Figure 6 is a section on the line 6—6 of Figure 5.

Figure 7 is an elevation, partly in section, of the device with the heating means replaced by an air compressor attachment.

Figure 8 is a fragmentary elevation, partly in section, of the device with the heating means replaced by an air conduit.

In detail, the invention consists of an elongated tubular casing 10, cylindrical in cross section, open at both ends and having one end formed in a gradually and outwardly flared mouth 11. The opposite end of the casing is externally threaded and is fitted with a spider 12 supporting a bearing 13 for one end of a longitudinally extending shaft 14, disposed within the casing and journalled at its other end in a bearing 15 carried by the ends of a plurality of peripherally spaced, outwardly bowed arms 16 extending longitudinally from the flared end

11 of the casing. A collar 17 retained by a set screw 18 is secured on the shaft for maintaining same in position against shifting, the collar engaging against the bearing 15. 60

In the flared end or mouth 11 of the casing is arranged a suction fan for drawing air within the casing. This fan is made up of four blades 19, mutually arranged at right angles and attached at their inner ends to the shaft 14 for rotation therewith. These blades are pitched at an angle of 45 degrees and are united at their outer ends by a peripheral, annular band 20 formed integral with the blades and revolving within the cage formed by the arms 16. The cage and casing mouth 11 form the intake through which air is drawn by the fan and discharged into the body of the casing. 70

Formed integral with the shaft 14 and extending between the bearing 13 and the fan, is a spiral screw conveyor web 21, one end of which abuts and merges into one of the fan blades 19. The radial dimension of the web 21 is such that it has a close fitting engagement with the walls of the casing 10 throughout the major portion of its length. Power for rotating the shaft, fan and web is applied to a driven pulley 22 on the end of the shaft which extends beyond the bearing 85 15.

A flared cylindrical nozzle 23 is detachably arranged, by threading engagement, over the outlet end of the casing 10. The interior of this nozzle forms a chamber 24, 90 in which air issuing from the casing through the spider 12 may be preliminarily heated by a heat source 25, in this instance an electric light bulb, the socket 26 of which is carried at the center of a spider frame 85 formed of a plurality of radially arranged arms 27 of triangular cross section and in alignment with the arms of the spider 12, which arms are also of triangular cross section, all as best shown in Figure 6. One of the spider arms 12 is provided with an oil bore 28 for the bearing 13, while a bore 29 is provided in one of the arms 27 for the wires (not shown) connecting the light 25 with its supply. 100

Disposed across the discharge end of the nozzle 23 is a screen or network of copper wires of small diameter, 30. This screen is carried by the nozzle, being suitably insulated therefrom, and is connected in series 110 with the leads 31 and 32 of an electrical circuit (not shown) by which the wires are

energized to form an electric heating grid across the nozzle. A series of spark gaps 33 are formed in the grid, and the sparking at these gaps acts to heat air discharged 5 from the nozzle, when the shaft 14 is rotated to actuate the device.

As shown in Figure 7, the discharge end 10 of the casing 10 may be fitted with a cap 34 threaded thereover in place of the nozzle 10 shown in Figure 1. The cap is provided with a discharge nipple 35 for connection with a tire air hose, whereby the apparatus 15 may be employed as an air pump for inflating tires. As shown in Figure 8, the discharge end of the casing 10 may also be fitted with a different form of cap 36, threaded thereover and formed with a constricted neck 37 arranged for connection with a relatively large air conduit 38, employed for 20 filling air tanks.

It will be apparent that in the operation of the device, which may be attached to a vehicle in any suitable manner, air drawn into the casing 10 by the fan is initially 25 compressed by the constricting action of the mouth 11. The conveyor web 21 acts to propel the air through the body of the casing, projecting it through the discharge end with considerable velocity and in great volume. 30 With the heating elements contained in the chamber 24 and nozzle 23, there will be a sustained blast of hot air issuing from the apparatus in front of the vehicle by which it is carried, which will effectively dispel fog and mist.

While in this preferred embodiment of the invention I have shown and described certain details entering into the construction and operation thereof, I desire it to be understood 40 that the invention is not to be limited thereto, but that any desired changes and modifications may be made in the structural

details thereof as will fall within the scope of the invention as claimed.

I claim:

1. Means for dispelling fog, comprising an elongated tubular casing open at both ends, an enlarged mouth formed at one end of said casing, a plurality of bowed arms extending outwardly from said end, a bearing carried by said arms, a spider in the opposite end of said casing, a bearing carried by said spider, a shaft journaled in said bearings and extending longitudinally through said casing, means for rotating said shaft, a shaft attached air propelling unit within said casing for pumping air through said casing and discharging from one end thereof, a flared nozzle for threaded engagement with the discharge end of said casing, and a heating unit arranged over the mouth of said nozzle.

2. Means for dispelling fog, comprising an elongated tubular casing open at both ends, a flared enlarged mouth formed at one end of the casing, a bracket carried by said mouth, a support secured in the opposite end of said casing, a shaft extending longitudinally through said casing and journaled between said support and bracket, a fan rigidly secured to said shaft in the enlarged mouth of said casing, a spiral propeller on said shaft and extending through the casing, one end of said propeller being formed integral with a blade of said fan in a continuation thereof, said fan being of a diameter greater than that of said spiral propeller, means for rotating said shaft for driving said fan and propeller, and means for heating air carried through said casing.

In testimony whereof I affix my signature.

ADOLF RIHO.
